UNITED STATES PATENT OFFICE.

WILLIAM R. TINGLE, OF CHARLOTTE, NORTH CAROLINA.

NECKTIE HOLDER.

Application filed March 30, 1922. Serial No. 543,119.

To all whom it may concern:

Be it known that I, WILLIAM R. TINGLE, a citizen of the United States of America, and resident of Charlotte, in the county of 5 Mecklenburg and State of North Carolina, have invented certain new and useful Improvements in Necktie Holders, of which the following is a specification.

This invention relates to brackets, and 10 particularly to a device for holding neckties, ribbons or the like.

An object of this invention is to provide a support for articles such as indicated, to be hereinafter specifically referred to as "neckties," by which the neckties can be applied 15 to or removed from the support expeditiously and without liability of creasing or crumpling the neckties.

It is a further object of this invention to 20 produce a support for neckties which may be readily suspended from a support anchored in the wall or the like, the said holder projecting preferably outward approximately horizontally in convenient position 25 to be used in applying neckties to it, so that the device constitutes not only a support for maintaining the neckties in an orderly condition, but so exhibits them in order that proper selection can be made.

It is a still further object of this invention 30 to produce a necktie holder of the character indicated which will be comparatively inexpensive to manufacture and that can be folded to occupy comparatively small space 35 while being transported or stored.

With the foregoing and other objects in view, the invention consists in the details of construction, and in the arrangement and combination of parts to be hereinafter more 40 fully set forth and claimed.

In describing the invention in detail, reference will be had to the accompanying drawings forming part of this application, wherein like characters denote correspond- 45 ing parts in the several views, and in which—

Figure 1 illustrates a view in perspective, showing a necktie holder embodying the invention;

Figure 2 illustrates a sectional view of a 50 fragment of the holder, showing the connection of the bail therewith; and

Figure 3 illustrates a detailed plan view of the joint between the ends of the holder.

In these drawings 5 denotes a relatively 55 straight section of resilient material, pref-

erably metal, having integral extensions 6 and 7 that are bowed or curved and have their ends overlapping to form the joint, as shown at 8. Preferably, the end of the extension 6 is offset slightly, as shown at 9, to form a seat 10 for the end of the extension 7, and the said extension 6 preferably terminates in a slightly outwardly bent lip 11 that facilitates the application of the necktie between the two ends of the extensions, it being of course understood that these extensions are to be forced apart to produce a clearance for the insertion of the tie which may be hung on the support.

The device is of such dimensions that it will hold a great number of ties, and of course the size may be changed to suit particular requirements.

Apertures are formed in the extensions as 75 shown at 12, at points near their merger with the straight portion 5, and these apertures form clearances for the reception of the bail or hanger 13 by which the holder is suspended or supported. Preferably, the 80 bail has an eye or loop 14 to receive a nail or other suspending device.

The bail has portions extending through the apertures 12, as shown at 15 and 16, so that the bail may swing to the position shown in Fig. 1, or it may be swung downwardly from the position in which it is shown in Fig. 1, to embrace the portions 6 and 7, it being the purpose of the inventor that the bail shall be slightly larger than 90 the support in order that it will nest with relation to it when folded. The bail terminates in angularly disposed portions 17 and 18 which engage the under edges of the extensions 6 and 7 and produce a bracing 95 action by which the holder is retained in horizontal position when the bail is hanging vertically, and, as stated, the relation of parts is such that the bail may be swung to a folded position when the device is not in 100 use.

From an inspection of the drawing and from the foregoing description, it will be understood that the device can be constructed of two pieces of metal, and can be made by the stamping and bending processes so that the cost of production will be comparatively small.

I claim:

1. In a necktie holder, a member having 110 extensions projecting outwardly therefrom, the ends of the said extensions overlapping

each other, a bail extending through the extensions and pivoted thereon, the said bail having angularly disposed portions underlying the said extensions for limiting the movement of the bail and member with relation to each other in one direction.

2. In a necktie holder, a body having overlapping resilient ends adapted to be forced

apart, a bail having ends extending through the holder whereby there is relative pivotal movement of the bail and holder, and angularly disposed extensions of the bail adapted to underlie the edge of the holder and forming supports to limit the relative oscillatory motion of the said holder and bail.

WILLIAM R. TINGLE.
